To all whom it may concern:

Be it known that I, Huna L. Apfelbaum, a citizen of Poland and resident of the Borough of Brooklyn, in the county of Kings, city and State of New York, have invented a new, original, and ornamental Design for a Container Cap, of which the following is a specification, reference being had to the accompanying drawing, forming part thereof.

Fig. 1 is a top view of a container cap showing my new design.

Fig. 2 is a front view of the same.

The characteristic features of my design for container cap reside in the flat upper surface on the outstanding base flange parallel to the flat periphery of the top surface of the cap and the tops of the ribs and in the substantially flat upright side surfaces of the ribs and the cylindrical side surface of the cap between the ribs, all as shown.

I claim:

The ornamental design for a container cap, substantially as shown and described.
